CLAIM

The ornamental design for a vertical computer front panel, as shown and described.

DESCRIPTION

FIG. 1 is a front elevational view of a vertical computer front panel showing our new design;

FIG. 2 is a top plan view thereof;

FIG. 3 is a left side elevational view thereof;

FIG. 4 is a back elevational view thereof;

FIG. 5 is a bottom plan view thereof; and,

FIG. 6 is a right side elevational view thereof.

The broken lines are shown in FIG. 4 for illustrative purposes only and form no part of the claimed design.
